Primary Examiner — Lilyana Bekic*Assistant Examiner* — Courtney J Clark-Rasheed(74) *Attorney, Agent, or Firm* — CHIARA IP LAW PLLC; Nicholas P. Chiara(57) **CLAIM**

The ornamental design for the grill as shown and described.

DESCRIPTION

FIG. 1 is a perspective view of the grill showing the new design;

FIG. 2 is a front view thereof;

FIG. 3 is a rear view thereof;

FIG. 4 is a right-side view thereof;

FIG. 5 is a left-side view thereof;

FIG. 6 is a top view thereof; and,

FIG. 7 is a bottom view thereof.

The broken lines in the drawings depict portions of the grill that form no part of the claimed design.
